UNITED STATES PATENT OFFICE.

SIGMUND STEINHARDT, OF NEW YORK, N. Y.

HOLD-UP ALARM.

Application filed July 3, 1926. Serial No. 120,396.

The present invention is concerned with the provision of an alarm mechanism which may have a wide range of utility in the arts, which finds its preferred embodiment 5 in a hold-up alarm adapted for use in stores, offices, or other places of business where cash or valuables are being handled.

An object of the present invention is to provide an alarm mechanism with which a 10 merchant or business man when held up, may signal for help without attracting the attention and without the knowledge of the bandit.

More specifically an object of the invention 15 is to provide an alarm circuit controlling mechanism in the nature of a depressible foot rail which may extend the entire length of a counter, so that when a tradesman is held up, he may place his foot at 20 any point on the rail, and close an alarm circuit.

A further object of the invention is to provide foot-operated circuit controlling means, which will be silent in operation, 25 which will be simple and practical in construction, rugged, durable and efficient in use, comparatively inexpensive to manufacture, capable of ready installation in a small amount of space, and of neat and attractive 30 appearance.

With the above noted and other objects in view, the invention consists in certain novel features of construction and combinations and arrangements of parts, as will be 35 more fully hereinafter set forth and pointed out in the claims. The invention may be more fully understood from the following description in connection with the accompanying drawings, wherein—

40 Fig. 1 is a wiring diagram of the alarm circuits, the foot rail circuit closer being illustrated somewhat schematically.

Fig. 2 is an enlarged longitudinal sectional detail through the foot rail and its associated parts, taken on the staggered line 2—2 of Fig. 3.

Fig. 3 is a transverse sectional detail on the line 3—3 of Fig. 2.

Fig. 4 is an enlarged view of the audible 50 signal and the switch for the visible signal circuit, showing the switch retained in inoperative position, the dotted lines indicating the closed position of the switch.

Fig. 5 is a fragmentary plan view of the 55 foot rail mechanism with the switch bar removed.

It is to be understood at the outset that the particular use to which the foot operated circuit closing mechanism of the present invention is applied, is subject to a wide range 60 of variations, and that the point at which the rail is installed is also immaterial to the present invention.

The foot rail itself is adapted to be secured in any appropriate manner to the floor, as 65 for instance behind a counter in a store, and includes an elongated bar 10 of wood or other non-conducting material having a groove 11 in its upper surface for the reception of a lead wire 12. This lead wire may 70 be connected through a battery 13 to one side of a circuit interrupter 14. At intervals along the groove 11 and alternately on opposite sides of the groove there are provided a series of contacts in the nature of ordinary 75 wood screws 15. The lead wire 12 is passed out of the groove and under the heads of these screws.

The other side of the circuit interrupter 14 is connected through a lead wire 15 to a 80 cover plate 16 of conducting material, formed with longitudinal flanges 17 straddling the bar 10. The cover plate is normally spaced above the bar and out of contact with the screws 15 by a series of bowed 85 plate springs 18, the ends of which rest on the rails 10, and the intermediate portions of which support the bar 16. Longitudinal shifting movement of these springs is restricted by stop pins 19 projecting from the 90 upper surface of the rail 10.

Relative longitudinal movement of the cover plate 16 and rail or bar 10 is prevented by the use of screws 20 passed through the flanges of the cover plate into 95 the sides of the bar. These screws work in openings 21 in the flanges which are of sufficient depth to permit depression of the cover plate 16 to move it into engagement with one of the contacts 15.

The cover plate 16 serves in effect as a switch bar. It is made of thin brass stock, or of some other material sufficiently thin gauged to permit local flexing of the switch bar. Thus when an operator places his foot on the switch bar 16 at any point, the bar will be locally depressed to engage one of the contacts 15 and close a circuit through the interrupter 14.

While I have shown a circuit interrupter, 110 it will be apparent that various other types of audible or visible signal mechanisms

might be directly controlled and substituted for the circuit interrupter.

I find that the use of the circuit interrupter is particularly desirable however, in that such interrupter may be used as a mechanical detent for the spring pressed switch of a visible signal circuit. This circuit has been indicated at 25, and the visible signals at 26. In the circuit 25, is a knife switch 27 normally acted upon by a spring 28 to close the circuit. The handle of the knife switch carries an offset arm 29 having an opening 30 therein, through which the hooked end 31 of the circuit interrupter armature 32 may be inserted. Armature 32 thus serves as a mechanical detent to retain the knife switch 27 out of operative position. When the armature is attracted by its magnet 33 however, the handle of the switch 27 will be released and the signal circuit 25 will be closed.

It will be apparent that the audible signal 14 may be located at any desirable location remote from the circuit closing foot rail, and 25 that the visible signals may be located either on a central panel board, at the police station, outside of a store, or wherever desirable.

Various changes and alterations might be 20 made in the general form and arrangement of parts described without departing from the invention. Hence I do not wish to limit myself to the details set forth, but shall consider myself at liberty to make such 25 changes and alterations as fairly fall within the spirit and scope of the appended claims.

I claim:

1. Foot operated circuit closing mechanism for a holdup alarm including an elongated substantially rigid base bar of non-conducting material adapted to be placed upon the floor, a series of springs supporting a flexible conductive switch bar in spaced relationship to the base bar, a plurality of contacts connected to a common lead wire and arranged at spaced points along the base bar, whereby a circuit may be closed when the switch is locally depressed to compress adjacent springs and engage any one of said contacts, said base bar being grooved to receive the lead wire, the contacts comprising studs arranged alternately on opposite sides of the groove and in electrical communication with the lead wire.

2. Foot operated circuit closing mechanism for a holdup alarm including an elongated substantially rigid base bar of non-conducting material adapted to be placed upon the floor, a series of springs supporting a flexible conductive switch bar in spaced relationship to the base bar, a plurality of contacts connected to a common lead wire and arranged at spaced points along the base bar, whereby a circuit may be closed when the switch is locally depressed to compress adjacent springs and engage any one of said contacts, said springs comprising bowed plate-like elements having their ends resting on the base bar and their intermediate portions supporting the switch bar, and pins in the base bar engageable with the ends of the springs to limit longitudinal displacement thereof.

SIGMUND STEINHARDT.
